BOAT PADDLE

Joseph R. Roberts, Little Rock, Ark.

Application February 17, 1959, Serial No. 54,638

Term of patent 14 years

(Cl. D71—1)

Fig. 1 is a front view of a boat paddle showing my new design;

Fig. 2 is a side view thereof;

Fig. 3 is a top view thereof;

Fig. 4 is a rear perspective view of that portion of the paddle shown in full lines in Figs. 1 and 2; and

Fig. 5 is a front view of the fragmentary portion shown in Fig. 4, the broken lines indicating the hand and forearm of a user being for illustrative purposes only.

The dominant features of my design reside in the portions shown in full lines.

I claim:

The ornamental design for a boat paddle, as shown and described.
